BELT TIGHTENER

Filed May 9, 1930

UNITED STATES PATENT OFFICE

CHARLES M. McRAVEN, OF TULSA, OKLAHOMA

BELT TIGHTENER

Application filed May 9, 1930. Serial No. 451,032.

My invention relates to improvements in belt tighteners, particularly adapted for use in conjunction with the band wheel belt of well pumping apparatus.

- 5 It is an object of the invention to provide a device of the above-mentioned character which will automatically take up the slack of the belt and exert a constant pressure on the belt at all times.
- 10 Another object of the invention is to provide a device of the above-mentioned character which is simple and durable in construction, reliable and efficient in operation and inexpensive to manufacture.

- 15 Other objects and advantages of the invention will be apparent during the course of the following description.

- 20 In the accompanying drawings, forming a part of this specification and in which like numerals are employed to designate like parts throughout the same,

Fig. 1 is a top plan view of the device in use,

Fig. 2 is a side elevation view of the device, partly in longitudinal section, and,

Fig. 3 is an enlarged top plan view of the same.

In the drawings, wherein for the purpose of illustration, I have shown a preferred embodiment of my invention, the numeral 5 denotes a vertical post mounted in a concrete base 6, the top of the base being covered by a metal plate 7 secured to the base by bolts 8, through which the post extends. The upper end 9 of the post is reduced forming the shoulder 10 which supports the bearing plate 11. Extending laterally from the upper end of the post is a horizontal arm 12 formed from channel iron, the outer end of the arm having a vertical spindle 13 mounted on its top face on which the idler pulley 14 is journaled. The inner end of the arm 12 is fitted over the reduced end of the post and has a sleeve 15 depending from the underside 45 of the arm, which is connected to the arm by

bolts 16 which extend through the arm and flange 17 surrounding the sleeve. Ball bearings 18 are provided between the arm and bearing plate 11, rotatably supporting the arm on the post and roller bearings 19 are disposed between the post and sleeve beneath the bearing plate, being held within the sleeve by the collar 20 mounted on the post and secured in place by the set screw 21. The arm 12 is secured upon the post by the bearing cap 22 which is secured to the post by the bolt 23 and holds the ball bearings 24 in bearing relation to the top face of the arm. A coil spring 25 is mounted on the post directly below the collar 20 having one end secured to the post, as at 26, and its opposite end secured to the lug 27 depending from the sleeve 15, as at 28. A bearing sleeve 29 is mounted on the lower end of the post above the plate 7 having roller bearings 30 therein which are held in place by the collar 31 secured on the post by the set screws 32. An angularly disposed brace bar 33, also formed of channel iron, extends between the bearing sleeve 29 and arm 12, its lower end being welded to the sleeve, and its upper end being secured to the underside of the arm by bolts 34. Depending from the underside of the arm 12, adjacent its outer end is an eye-bolt 35, to which a cable may be attached for pulling the arm 12, to an inoperative position, or in the direction which the arm is moved by the spring 25, to increase the pressure of the idler pulley on the belt, when desired. The base 6 is positioned in the ground adjacent the belt 36 of the band wheel 37, so that the arm 12 extends beneath the belt, as clearly shown in Fig. 1.

In operation, the arm 12 supporting the idler pulley 14 is turned on the post 5, against the tension of the coil spring 25, before the belt 36 is placed around the idler pulley. Upon release of the arm, the tension of the coil spring turns the arm so that the idler pulley presses against the belt taking up the 90

slack and thereafter, holds the belt tight by exerting a constant pressure on the belt. The support for the idler pulley is sturdily constructed so as to withstand the shocks and strains to which it is subjected while performing the function for which it is adapted.

It is to be understood that the form of my invention herewith shown and described is to be taken as a preferred example of the same and that certain changes in the shape, size and arrangement of the parts may be made without departing from the spirit of the invention or the scope of the subjjoined claims.

Having thus described my invention, I claim:

1. A belt tightener comprising a base, a vertical post mounted in said base, a horizontal arm having one end rotatably mounted on said post, an idler pulley mounted in a horizontal plane on the outer end of said arm, a brace bar having one end connected to said arm and its opposite end rotatably mounted on said post and a coil spring mounted on said post having one end connected to said post and its opposite end connected to said arm.

2. A belt tightener comprising a base, a vertical post mounted in said base, a bearing plate mounted on the upper end of said post, a horizontal arm having one end fitted over said post having a depending sleeve surrounding said post, ball bearings between the bearing plate and arm, roller bearings between the sleeve and post, a bearing cap mounted on the upper end of said post, an idler pulley mounted on the outer end of said arm in a horizontal plane, and a coil spring mounted on said post having one end connected to said post and its opposite end connected to said sleeve.

3. A belt tightener comprising a base, a vertical post mounted in said base, a horizontal arm having a depending sleeve at one end adapted to fit over the upper end of said post, ball bearings mounted in said sleeve rotatably supporting said arm on said post, an idler pulley mounted in a horizontal plane on the outer end of said arm, a brace bar having one end connected to said arm and its opposite end rotatably mounted on said post, and a coil spring mounted on said post having one end connected to the post and its opposite end connected to said sleeve.

4. A belt tightener comprising a base, a vertical post mounted in said base, a horizontal arm having a depending sleeve at one end adapted to fit over the upper end of said post, ball bearings mounted in said sleeve rotatably supporting said arm on said post, an idler pulley mounted in a horizontal plane on the outer end of said arm, a brace bar having one end connected to said arm, a roller bearing connected to the opposite end of said brace bar adapted to be mounted on

said post, and a coil spring mounted on said post having one end connected to the post and its opposite end connected to said sleeve.

5. A belt tightener comprising a fixed post, an arm extending laterally from said post and rotatably mounted thereon, an idler pulley mounted on the outer end of said arm, a brace bar having one end connected to said arm and its opposite end rotatably mounted on said post and a coil spring mounted on said post having one end connected to said post and its opposite end connected to said arm.

In testimony whereof I affix my signature.
